UNITED STATES PATENT OFFICE.

THOMAS N. RUSSELL, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

CARLINE.

1,096,462.

Specification of Letters Patent. Patented May 12, 1914.

Application filed March 12, 1914. Serial No. 824,156.

To all whom it may concern:

Be it known that I, THOMAS N. RUSSELL, a citizen of the United States, residing at Chicago, in the county of Cook and State 5 of Illinois, have invented certain new and useful Improvements in Carlines, of which the following is a specification, reference being had to the accompanying drawings.

This invention relates to improvements in 10 carlines, and particularly to that class of carlines comprising a plurality of metal bars suitably connected together and at their ends provided with means adapted to engage and be secured to the usual side plates of 15 a car.

The leading objects of the invention are to provide a construction wherein said bars are so formed and arranged with relation to each other as to insure a device of great 20 strength; to provide a novel construction of knee-iron at each end of the said bar members of the carline for attachment to the side plates, which knee-iron will very securely hold the ends of such bar members together 25 and at the same time will offer no obstruction between the ends thereof and the inner face of the side-plate; and to improve generally the construction of devices of the character specified.

30 I accomplish these objects by the construction and arrangement of parts as shown in the drawings and hereinafter particularly described.

That which I believe to be new will be 35 pointed out in the claims.

In the drawings:—Figure 1 is a side elevation of my improved carline, to the lower bar of which is bolted a wooden stringer, to the under side of which sheathing may be 40 secured, as usual; Fig. 2 is a plan view of the same parts that are shown in Fig. 1; Fig. 3 is a side elevation of my improved knee-iron with a portion of the two bar members of the carline attached thereto; Fig. 4 is a view similar to Fig. 3, but looking at the opposite side of the parts; Fig. 5 is a perspective view of the novel 45 knee-iron; Fig. 6 is a vertical section through the center of the carline, taken at line 6—6 of Fig. 1; Fig. 7 is a vertical section through the carline, taken at line 7—7 of Fig. 3, or line X—X of Fig. 1; and Fig. 8 is an end view of the device, as seen 50 from a point in the line 8—8 of Fig. 4.

55 My improved carline comprises four prin-

cipal parts or members, viz., a tie-beam, a truss-beam, and two knee-irons. The tie-beam consists, as shown, of an iron rolled into L-shape to thereby form a vertical and a horizontal flange, the vertical flange being indicated by 10 and the horizontal flange by 11. The other beam is of similar design and cross-section, its vertical flange being indicated by 12 and its horizontal flange by 13. The vertical flange in the first- 60 mentioned bar extends upwardly from its horizontal part while the corresponding flange in the second-mentioned bar extends downwardly from its horizontal part. The bar 12—13 is raised at its central portion 65 and at such raised central portion is connected to the bar 10—11 by a suitable strut 14 riveted to the vertical flanges 10 and 12. From the raised central portion the upper bar 12—13 inclines downward to bring its 70 end portions opposite the end portions of the other bar 10—11 so that the respective vertical flanges are in contact, as clearly shown in Figs. 7 and 8. These two bars can be, therefore, said to stand back-to-back at 75 80 their ends inasmuch as the horizontal flanges 11 and 13 extend in opposite directions. The two bar members form a truss-beam and their end portions are rigidly secured together by the novel knee-iron 85 shown, one such knee-iron being applied at each end of the truss-beam. The knee-iron mentioned is formed by casting and comprises a horizontal plate 16 adapted to rest on the upper surface of a side plate of a 90 car, the short down-turned flange 17 at the outer end of such plate resting against the outer face of such side plate.

18 indicates a vertical wall formed with the horizontal plate 16 and adapted to rest against the inner face of the said side plate, but, as will be hereinafter pointed out, such vertical wall portion 18 is not interposed between the said side plate and the adjacent 95 end of the truss-beam, but is provided with a suitable aperture to permit the passage therethrough of the ends of the angle-iron bars that constitute such truss-beam.

19 indicates a rearward extension of the horizontal plate portion 16, such extension 100 103 105 108 110 113 having a narrow depending flange 20 at one edge, and a wide depending flange 21 at the other edge, the space between such two last-named flanges being wide enough to receive between them the bar member

12—13 and the vertical flange 10 of the other bar member, as clearly shown in Fig. 7. These flanges 20 and 21 are also integral with the vertical wall 18, and the narrow flange 20 is widened at its juncture with said wall 18 to form a strengthening fillet, indicated by 22, see Fig. 7.

23 indicates a horizontal wall-member extending out from the vertical wall-member 18 and of the same length in the construction shown as the horizontal extension 19. The horizontal wall-member 23 is located a sufficient distance below the lower edge of the wide flange 21 of said extension 19 to permit of the free passage between such edge and horizontal wall 23 of the horizontal flange 11 of the angle iron bar 10—11, as clearly shown in Fig. 7.

24 indicates a wide vertical flange extending upwardly from one edge of the horizontal wall 23, and 25 indicates a narrower vertical flange extending up from the other edge thereof, both of said flanges, of course, being integral with the vertical wall 18, and at the juncture of the short flange with the said wall 18 said flange 25 is curved to form a strengthening fillet 26, as best shown in Fig. 5. The two flanges are located a distance apart sufficient to receive between them the bar 10—11 of the truss-beam and the vertical flange 12 of the other bar of such beam, as also clearly shown in Fig. 7.

From the foregoing description it will be seen that my improved knee-iron comprises what may be termed two channel or U-shaped brackets, one of them inverted, and so disposed with relation to each other that a down-turned side flange of one lies opposite to and a distance from an upwardly-projecting flange of the other. Such construction permits the knee-iron to be slipped over the end of the truss-beam with the back-to-back flanges 10 and 12 between the spaced vertical flanges 21 and 24, the horizontal member 13 of the bar 12—18 lying parallel to and in close proximity to the extension 19, and the horizontal flange 11 of the bar 10—11 lying in close proximity to the horizontal wall 23.

50 In order that the truss-beam formed of the two united angle-iron bars may extend the full width of the car between the side plates thereof I form an opening through the vertical wall 18 of each knee-iron, such opening corresponding substantially in size and shape to the end cross-section of the truss-beam, and through such opening the end of the truss-beam projects. Such opening (see Figs. 7 and 8) is indicated by 27. The two bar-members of the truss-beam where brought together at their end portions are secured together and to the knee-iron by rivets 28 passed through aligned openings in the vertical flanges 21 and 24 of the knee-iron, and the back-to-back vertical

flanges 10 and 12 of the two bar-members. Each knee-iron is adapted to be secured to a side plate of a car by a bolt passed through an opening 29 in the horizontal plate 16, and through openings 30 in the lower part of the wall 18 of such knee-iron.

31 indicates a strengthening rib along the top of the knee-iron, which is preferably bifurcated at its outer portion, as shown in Fig. 5.

32 indicates a wooden stringer resting on the horizontal flange of the lower bar-member 10, and secured in place by bolts 33, as usual, that pass through such stringer and through the vertical flange of such bar member. As shown, it is further secured in place by a lip 34 cut from the central strut 14 and turned down to rest against the top surface of such stringer.

By my invention I form a very strong carline, which is so securely attached to the side plates of a car, and braced thereto, as to preclude any possibility of breakage or weakening under all ordinary conditions of use.

What I claim as my invention and desire to secure by Letters Patent, is—

1. A carline comprising in combination two angular bar members each having a flange located opposite a flange of the other member, a knee-iron having two rearwardly-extending vertical flanges spaced a sufficient distance apart to receive between them the end portion of one of said bar members and a part of the end portion of the other of said bar members, and means for securing said bar members to one of said flanges of the knee-iron.

2. A carline comprising in combination two angular bar members each having a flange located opposite a flange of the other member, a knee-iron having two rearwardly-extending vertical flanges spaced a sufficient distance apart to receive between them the end portion of one of said bar members and a part of the end portion of the other of said bar members, a third vertical rearwardly-extending flange between said two last-named flanges, and means for securing said bars in place between one of said two first-mentioned flanges of the knee-iron and said third flange.

3. A carline comprising in combination two angular bar members each having a flange located opposite a flange of the other member, a knee-iron having a channel-shaped bracket that receives the end portion of one of said bar members and a part of the end portion of the other bar member, and means for securing said bar members to said bracket.

4. A carline comprising in combination two angular bar members each having a flange located opposite a flange of the other member, a knee-iron having a vertical wall

adapted to rest against the inner face of a side plate of a car and provided with an opening through which an end of the bar members passes, said wall also being provided with a channel-shaped bracket that receives the end portion of one of said bar members and a part of the end portion of the other bar member, and means for securing said bar members to said bracket.

5 5. A carline comprising in combination two angular bar members each having a flange located opposite a flange of the other member, a knee-iron adapted for attachment to a side-plate of a car and comprising two 10 channel-shaped brackets, one of which is inverted, the inner flange of each extending into the channel of the other bracket and being spaced apart to receive between them the said flanges of the bar members, and means 15 for securing said bar flanges and said bracket flanges together.

6. A carline comprising in combination two angular bar members each having a flange located opposite a flange of the other member, a knee-iron adapted for attachment to a side plate of a car and having a vertical wall provided with an opening through which an end of the bar members passes, said wall also being provided with two channel-shaped brackets, one of which is inverted, the inner flange of each extending into the channel of the other bracket and being spaced apart to receive between them the said flanges of the bar members, and means 30 for securing said bar flanges and said bracket flanges together.

7. A carline comprising in combination two angular bar members each having a flange located opposite a flange of the other member, a knee-iron adapted for attachment to a side-plate of a car and having two channel-shaped brackets, each of which receives the end portion of one of said bar members and a part of the end portion of the other 40 bar member, and means for securing the bar members to and between two of the side walls of the brackets.

8. A carline comprising in combination two angle-iron bars each having a horizontal flange and a vertical flange, said bars at their ends lying side by side and having their horizontal flanges extending in opposite directions, a knee-iron having means 50 for attachment to a side plate of a car and provided with two downwardly-extending vertical flanges that receive between them one of said angle-iron bars and the vertical flange of the other of said bars, and also pro-

vided with two upwardly-extending flanges that receive between them said other bar and the vertical flange of the first-mentioned bar, and means for securing the vertical flanges of the angle bars to and between two of the flanges of said knee-iron.

9. A carline comprising in combination two angle-iron bars each of which has a horizontal flange and a vertical flange, said bars at their ends lying side by side and having their horizontal flanges extending in opposite directions, a knee-iron having a horizontal plate portion and a vertical wall adapted to rest against the upper face and one side respectively of a side plate of a car, said vertical wall having an opening into which the said bars project, and said wall having connected therewith two downwardly-extending and two upwardly-extending flanges, one of said bars and the vertical flange of the other bar being located between said two downwardly-extending flanges, and said other bar and the vertical flange of the first-mentioned bar being located between two upwardly-extending flanges, and means for securing the vertical flanges of the angle-bars to and between one of said downwardly-extending flanges and one of said upwardly-extending flanges.

10. A carline comprising in combination two bars connected together, a knee-iron having a horizontal plate portion and a vertical wall adapted to rest against the upper face and one side respectively of a side plate of a car, said vertical wall having an opening into which the said bars project, and said wall having connected therewith two vertical flanges between which end portions of the said bars extend, and means for securing said bars and flanges together.

11. A carline comprising in combination two bars connected together, a knee-iron having a horizontal plate portion and a vertical wall portion adapted to rest against the upper face and one side respectively of a side plate of a car, a rear extension of said horizontal plate having a downwardly-extending flange, another horizontal wall or plate member extending in the same direction as the said extension but in a lower plane and provided with an upwardly-extending flange, and means for securing said bars between said two flanges.
